UNITED STATES PATENT OFFICE.

JOHN SHELLENBERGER, OF INDIANAPOLIS, INDIANA.

BOTTLE-WRAPPER.

SPECIFICATION forming part of Letters Patent No. 236,186, dated January 4, 1881.

Application filed November 23, 1880. (No model.)

To all whom it may concern:

Be it known that I, JOHN SHELLENBERGER, a citizen of the United States, residing at Indianapolis, in the county of Marion and State 5 of Indiana, have invented a new and useful Improvement in Bottle-Wrappers, of which the following is a specification.

My invention relates to bottle-wrappers; and the object of my improvement is to provide 10 the wrapper with strips at one or both ends, bent or twisted at right angles to the body of the wrapper, which will be elastic and protect said ware from breakage when packed. This object I accomplish by the device illustrated 15 in the accompanying drawings, in which—

Figure 1 represents a top view of a bottle inclosed in my improved wrapper. Fig. 2 is a top view of a bottle inclosed in a modified form of my wrapper. Fig. 3 is an elevation 20 of a bottle with a section of the wrapper. Fig. 4 is a plan view of a sheet of thin wood veneer or other suitable material forming the wrapper, as shown in Fig. 1; and Fig. 5 is a plan 25 view of a sheet of thin wood veneer or other suitable material, forming the modified form, as shown in the wrapper in Fig. 2.

Similar letters refer to like parts throughout the several views.

A represents a bottle; a, the body of the 30 wrapper.

The sheet of thin wood veneer or other suitable material is slit or cut into a number of narrow strips, b b², at one or both ends, and the base or root of each strip b is partially cut 35 on one side by a cross-cut at right angles to the slit, for the purpose of allowing the freed

part b of the strips to be bent outward at an angle to the other portion, b², of said strips, as shown in Figs. 1 and 4. Thus the bent-out portions b, in connection with the unbent portion b² of the strips, forms an angular elastic support at those parts. The same result is produced if the strips b of the modified form shown in Figs. 2 and 5 are not partially cut by a cross-cut at their bases, but simply bent 45 in the form of a twist at an angle to the body a of the wrapper, as shown.

These prepared wrappers are wrapped around bottles and other like articles in one or more sections, and the edges secured together by 50 pasting strips of paper around the part a.

The upper strips, b, may be bent up to the bottle-neck or left straight, as shown in Fig. 3, as desired.

Wrappers thus prepared—i. e., with the bent 55 strips b b²—form good, substantial, elastic bearings to keep the bottles apart when packed in cases and prevent breakage.

What I claim as new, and desire to secure by Letters Patent, is—

As a new article of manufacture, the thin 60 sheet wrapper a, having strips cut at one or both ends, and bent in the form of a twist at an angle to the body of the wrapper, substantially as shown and described.

In testimony whereof I have signed my name to this specification in the presence of two subscribing witnesses.

JOHN SHELLENBERGER.
